Inventor:

Josef Kälin,

By *Henry M. Jr.*
Attn.

UNITED STATES PATENT OFFICE.

JOSEF KÄLIN, OF OBERWINTERTHUR, SWITZERLAND.

ELEMENT FOR WAINGSCOTING.

Application filed March 25, 1921. Serial No. 455,564.

To all whom it may concern:

Be it known that I, JOSEF KÄLIN, a citizen of the Republic of Switzerland, residing at Oberwinterthur, Switzerland, have invented certain new and useful Improvements in Elements for Wainscoting (for which applications for patent have been filed in Switzerland, July 17, 1916, Patent No. 73,438; France, September 12, 1916, Patent No. 482,837; Italy, September 9, 1916, Patent No. 156,462; and in Germany, March 11, 1919, Utility Patent No. 702,112); and I do hereby declare the following to be a clear, full, and exact description of the invention, such as will enable others skilled in the art to which it appertains to make and use the same, reference being had to the accompanying drawing, and to letters or figures of reference marked thereon, which form a part of this specification.

This invention relates to elements or matched boards for wainscoting of that type in which more or less narrow boards are juxtaposed to form the wainscot.

My invention consists essentially in providing an element for wainscoting along its longitudinal edge with projecting means destined to cover over the joint between said element and the one to which it is juxtaposed in the wainscot, in order to hide any crack due to shrinkage which might take place.

The nature of the present invention will now be more particularly described with reference to the accompanying drawing which illustrates a constructional example of the same.

In this drawing:

Fig. 1 is a cross-section through a wainscot formed of several match boards connected by tongue and groove.

Fig. 2 is a front view of a wainscot.

Fig. 3 is a vertical section showing the manner of applying a base board.

In the embodiment of the invention shown in the Figures 1 and 2, the deals or matched boards 1 are provided with tongues on one

edge 2 and grooves 3 on their opposite edge, moreover each board 1 has a projecting border 4 along one of its longitudinal edges (its lower edge in Fig. 1) for the purpose of covering the joint 5 between two adjacent boards 1, towards the outside of the wainscot, in order to hide any gap of the joint 5, which might arise through shrinkage of the wood.

In this example the projecting border 4 forms part of the moulding 6 whose thickness is such that its thinnest part x is always thicker than the thickness y of the smooth part 7 of the body portion of the board 1. By this construction it will also be possible to effect a jointless fit of the wainscot against its base board and cornice for instance by planing off the moulding 6 as shown in Fig. 3. In this figure the molding 4 is planed off at a distance above the floor the height of the base-board 8, which is then set under the lower ends of the molding against a perfectly flat surface 9, free from grooves and recesses that collect dust and vermin.

With the fluted wainscoting commonly used, the groove appears at each joint in case of shrinkage. A wainscot made of match board according to my invention forms a closed compact covering, without visible subdivision, this being due to the fact that the smooth part 7 is countersunk with regard to the moulding 6.

I claim:

In a wainscoting element, a molding arranged adjacent to one of the longitudinal edges of the element and joining on to a flat portion of the element, the molding being integral with the flat portion and all the parts of the molding projecting above the face of the flat portion so that the molding can be planed off at places to the face of the flat portion.

In testimony that I claim the foregoing as my invention, I have signed my name.

JOSEF KÄLIN.
